CAN OPENER

William D. Husted, Shavertown, Pa.

Application July 17, 1950, Serial No. 174,325

3 Claims. (Cl. 30—16)

1

This invention relates to openers for cans and similar containers.

An object of this invention is to provide an opener of the container top puncturing type for cutting a hole in the top of a metal can; the device being so constructed that the size of the hole may be regulated, so that if desired a relatively large pouring hole may be formed in the top, and a second relatively small vent hole may be separately formed in the can opposite from the pouring hole.

It is another object of this invention to provide a can opener of the container top puncturing type having an adjustable pivot member so that the length of the arm supporting the cutting element may be varied and in which the pivot member also acts as a fulcrum for a lid lifting device also disposed on the opener for removing lids from glass jars or the like.

A further object of this invention is to provide an opener of this kind which is easily and quickly adaptable for use on either large or small containers, such as large size juice cans, beer cans, and also the various sizes of milk cans.

A further object of this invention is to provide a can opener of this kind which is of simple construction so as to be made of metal stampings with a minimum of operations.

With the above and other objects in view, my invention consists in the arrangement, combination and details of construction disclosed in the drawings and specification, and then more particularly pointed out in the appended claims.

Referring now to the drawings:

Figure 1 is a side elevational view showing my invention applied in position against the rim of a can, or the like container, for piercing and cutting a top wall of the container.

Figure 2 is a bottom plan view of the device shown in Figure 1, the handle portion indicated as broken to show that the length of the handle is variable.

Figure 3 is a fragmentary detail top plan view of the puncturing and cutting end of the device shown in Figure 1.

Figure 4 is a section on the line 4—4 of Figure 3.

Figure 5 is a side elevational view of a modified form;

Figure 6 is a top plan view of the puncturing and cutting end of the device shown in Figure 5;

Figure 7 is a section taken on the line 7—7 of Figure 6;

Figure 8 is a plan view of the blank form from which an element of the device in Figure 5 is formed;

Figure 9 is a second modification of the device shown in Figure 1.

Figure 10 is a sectional view taken on the line 10—10 of Figure 9.

Figure 11 is a plan view of a portion of an element of the device shown in Figure 9.

Figure 12 is a plan view of the blank from which an element of the device shown in Figure 9 is formed.

Figure 13 is a third modification of the device shown in Figure 1 shown in a side elevational view.

Figure 14 is top plan view of an element of the modification shown in Figure 13.

Figure 15 is a side elevation partly in section showing the operation of the device illustrated in Figure 1 as jar lid lifting means.

Figure 16 is a sectional view taken on the line 16—16 of Figure 2.

Referring to Figures 1, 2, 3 and 4 of the drawings, I have disclosed a preferred embodiment of my invention. The can opener there shown comprises a handle 15 having a downwardly bent forward portion 16 formed with an offset puncturing point 17 on the end thereof. The downwardly bent forward portion 16 has a longitudinally extending elongated slot 18 therein. The handle 15 is provided with a downwardly struck out lug 19 for use as a bottle cap or jar lid remover. Container or can rim gripping means 20 are slidably carried on the lower side of the forward handle portion 16. The rim gripping means is best seen in Figure 4 and includes a tubular body 21 formed with an outwardly extending circular flange 22 formed on the lower end thereof. The flange 22 has a marginal ridge 24 formed on the upper surface thereof to grip under the rim 11. The rim gripping means 20 are slidably mounted on the portion 16 by means of a rivet 23 or the like which is passed downwardly through the slot 18 and the center of the tubular body 21 and is then upset against the lower surface of the flange 22. The rim gripping means will thereby be carried by the slot 18 and may be adjusted longitudinally relative to the point 17. As seen in Figure 1, when it is desired to puncture the top of a container 10, the flange 22 of the rim gripping means is placed under the rim or bead 11 found on all such containers and the handle 15 is rocked upwardly thus urging the point 17 downwardly so as to puncture the container top. When it is desired to puncture a large hole in the container top, the rim gripping means is slidably moved to the rearmost portion of the slot 18, thus positioning the point 17 relatively far in from the rim 11. When it is desired

to punch a small hole in the container top, as for example, a vent hole, the rim engaging means 20 is slid to the most forward position possible in the slot 18, thus positioning the point 17 relatively close to the rim 11.

In Figures 5, 6, 7, and 8 I have demonstrated a possible modification of the device shown in Figure 1. Here, the slot 25 is formed with an enlarged opening 26 at the rear or inner end thereof. The rim gripping means 27 includes a member 28 formed from the blank shown in Figure 8 and securing means 29. The member 28 is formed with a rectangular plate 30 having a centrally located hole 31 which is disposed on the top surface of the handle portion 16. A downwardly bent portion or shank 32 extends from the forward edge of the plate 30 through the slot 25. The bottom end 33 of the shank 32 is then bent forwardly to provide rim gripping means. The securing means 29 consist of a stud 34 carried in the hole 31 and extending down from the lower surface of the plate 30 and having an enlarged head 35 formed on the bottom end thereof. In assembling the rim gripping means 27 to the handle 15, the enlarged head 35 is inserted downwardly into the opening 26 and the downwardly bent shank 32 into the slot 25. The rim gripping means 27 are then slid forwardly along the slot 25 and the inner or rear end of the slot is restricted by pinching the sides of the slot as at 36. Once the inner end of the slot is pinched off, the rim gripping means 27 are not removable from the slot 25.

In the modification shown in Figures 9, 10, 11, and 12, the rim gripping means is formed from a single stamped piece of metal, the blank of which is shown in Figure 12. As seen in Figure 11, the slot 37 has a transverse slot 38 formed at the inner end thereof. The rim gripping means 39 consists of a plate 40 having a bent down relatively narrow lug 41 formed integral with the rear edge of the plate 40, and extending through the slot 37. The end of the lug 41 has side extensions 42 and is reverted under the plate 40 and spaced downwardly therefrom. A shank 43 is formed on the forward edge of the plate 40 and extends through the slot 37. The bottom end 44 of the shank 43 is bent forwardly to provide rim gripping means. When it is desired to assemble the rim gripping means to the handle, the reverted portion having the side extensions 42 is inserted into the transverse slot 38 and the shank 43 is inserted into the slot 37. The rim gripping means 39 is then slid forwardly along the slot 37 and the rear end of the slot 37 is pinched off as at 45 to prevent the removal of the rim gripping means 39 from the handle 16. Since the lug 41 and the shanks 43 are longitudinally spaced apart, the rim gripping means are restrained from rotation relative to the slot 37. In the modification shown in Figures 5-8, the longitudinal spacing of the stud 34 and the portion 32 similarly prevents rotation of the rim gripping means relative to the handle.

Still another modification of my invention is disclosed in Figures 13 and 14, wherein still another form of rim gripping means 46 is shown. In this construction, the rim gripping means includes a stamped metal member 47 having a plate 48 disposed below the forward portion of handle 15. The plate is formed with a downwardly bent forward edge 49 and an upwardly bent lug 50 which is integral with the rear edge thereof. The bottom of the downwardly bent forward edge 49 extends forwardly, as at 51 and has an

arcuate cutout 52 in the forward edge thereof to provide two rim gripping feet 53. The plate 48 has a centrally located hole 54 therein to receive the reduced portion 55 of a lug 56 having an enlarged head 57 spaced upwardly therefrom. In assembling the rim gripping means 46 to the handle 15, the lug 56 is inserted into the slot from above, as shown in Figure 13, with the enlarged head 57 positioned above the handle 15. The reduced portion 55 is extended through the hole 54 and is then upset as at 58. Since the lug 56 is spaced forwardly of the upwardly bent lug 50 the rim gripping means 46 will be restrained from rotation.

In Figure 15 I have illustrated the operation of my device when in use as a jar lid remover. The jar or bottle 60 is shown with a lid or closure 61 sealing the top opening thereof, and the opener is positioned with the member 19 underlying a portion of the rim of the lid 61. The gripping means 20 is positioned at the end of the slot 18 closest to the puncturing point 17 so as to overlie a substantial portion of the lid. When the handle 15 is raised, the means 20 will provide a fulcrum and the moment arm between the fulcrum and the member 19 will be considerable so as to provide the maximum lift on the latter without mutilation of the lid. It is therefore possible to remove lids that are suctionally engaged on jars without rendering them incapable of further sealing of the jar. While I have only illustrated the modification shown in Figure 1 in operation as a lid removing device, it is understood that the modifications shown in Figure 5 and in Figure 9 may be similarly applied.

The rear end of the handle 15 is formed with an opposed pair of lid prying blades 62 which are formed by cutting out the lengthwise edges of the handle as at 63. These blades 62 have rounded edges 64 and 65 so that when a blade 62 is inserted between the lid 61 and the upper portion of the receptacle, the blade 62 may be rocked upwardly by rocking of the handle and the rounded edges will not crack or chip the receptacle. Where the blades have sharp corners such corners have a tendency to crack or break the glass container whereas with the rounded corners the container will not be cracked or chipped.

The above description and the drawings represent various modifications of my invention which have proved themselves adapted to easy production and fully able to fulfill the stated objects of the invention. However, various modifications in the details of the construction here disclosed may be resorted to without departing from my invention which is defined in the appended claims.

What I claim is:

1. A can opener comprising a flat tapered blade formed with an elongated lengthwise slot and an enlarged opening at the inner end of said slot, a can rim engaging member disposed on the lower side of said blade and including a shank loosely engaging through said slot and a plate disposed on the upper side of said blade, a headed securing member fixed to said plate and engaging loosely through said slot, said securing member being disposed in spaced relation with respect to said shank and cooperating with said shank in holding the latter and said rim engaging member against turning, the head of said securing member being initially inserted through said enlarged opening, and means restricting the inner end of said slot whereby said securing

member will be held against entering said enlarged opening.

2. A can opener comprising a flat tapered blade formed with an elongated lengthwise slot and an enlarged opening at the inner end of said slot, a can rim engaging member disposed on the lower side of said blade and including a shank loosely engaging through said slot and a plate disposed on the upper side of said blade, a headed securing member integral with said plate and engaging loosely through said slot, said securing member being disposed in spaced relation with respect to said shank and cooperating with said shank in holding the latter and said rim engaging member against turning, the head of said securing member being initially inserted through said enlarged opening, and means restricting the inner end of said slot whereby said securing member will be held against entering said enlarged opening.

3. A can opener comprising a flat handle, a

tapered can puncturing blade at one end of said handle and disposed on an oblique angle to the length of said handle, said blade having an elongated slot extending longitudinally thereof, a can rim engaging member disposed on the lower side of said blade, means secured to said member loosely extending through said slot securing said member to said blade whereby said member may be held on said blade for adjustment lengthwise of said slot.
